UNITED STATES PATENT OFFICE

LOUIS A. GEBHARD AND CORRIE F. RUDOLPH, OF WASHINGTON, DISTRICT OF COLUMBIA, ASSIGNEES TO WIRED RADIO, INC., OF NEW YORK, N. Y., A CORPORATION OF DELAWARE

CONDENSER SYSTEM

Application filed April 15, 1929. Serial No. 355,375.

Our invention relates to condenser systems in general and more specifically to adjustable condenser systems for high frequency electrical circuits.

5 One of the objects of our invention is to provide a compact and efficient adjustable condenser system for thermionic tube high frequency transmitters.

Another object of our invention is to provide a compact and efficient adjustable condenser system to be employed in electrically balanced circuit arrangements utilizing water cooled thermionic tubes.

10 Still another object of our invention is to provide a compact and efficient condenser system adapted to electrically balance an arrangement of thermionic tubes.

Other and further objects of our invention reside in certain structural features we employ whereby the condenser system is shielded and occupies a relatively small amount of the available space in high frequency transmitters.

Our invention will be more fully understood from the specification hereinafter following and by reference to the accompanying drawings, in which:

Figure 1 shows an end view in part section of our invention; Fig. 2 shows a top plan view of our invention; Figs. 3 and 4 show a side elevation of the condenser system of our invention; and Fig. 5 is a schematic circuit diagram showing the operation of the condenser system of our invention.

25 In high frequency transmitters it is necessary to employ some value of capacity to control the frequency characteristics of the circuits. In high power transmitters, thermionic tubes having their anodes cooled by a circulatory liquid, occupy considerable space. It is desirable to confine the apparatus in as small space as is consistent with efficiency. In the combined condenser system of our invention the capacity necessary to control the 30 frequency characteristics of the circuits and compensate or balance irregularities in the thermionic tubes, is confined within a small area with an increase in efficiency and stability of the transmitter resulting.

50 In Fig. 1 of the accompanying drawings,

an end view in part section shows a part of the combined condenser system of our invention. The combined condenser system illustrated in the accompanying drawings is of the design to be associated with two thermionic tubes. However, a single one of the tubes may be used or a cascade system of balanced tubes may be employed where the transmitting system so requires.

55 In Fig. 1, a socket 1, or retainer for the tube 2, is indirectly supported by the main framework of the transmitter. Socket 1 is provided with a clamping member 1a which locks and seals flange 2a of tube 2 against the fluid circulation compartment 1b of socket 1. 60 Flange 2a is integral with the anode of thermionic tube 2. Compartment 1b of socket 1 may be a metallic cylinder of sufficiently large dimensions to permit the anode of tube 2 to be supplied with proper circulation of the 65 cooling fluid. The lower section 1c of compartment 1b is provided with fluid conducting members 19 and 20 adapted to admit the fluid to and from container 1b. A cylinder 70 10, of metallic material, surrounds and is electrically connected to compartment 1b of socket 1. 75 Cylinders 4 and 5, of suitable metallic material, are of slightly different diameters; the inner wall of cylinder 4 bearing against the outer wall of cylinder 5. Cylinders 4 and 80 5 are supported by arm 3 and are electrically insulated and spatially positioned from socket 1 and cylinder 10. Portions 15 are cut away from cylinder 10 to prevent voltage discharge to arm 3. Cylinders 4 and 5 have sections 7 cut away, which sections may be of any dimension or shape desired. Sections 7 may comprise the equivalent of one half the area of either cylinder. An annular recess or groove is provided in cylinder 5 wherein a 85 spring member 9 bears against cylinders 4 and 5, thereby establishing an electrical connection between these members at all times. Cylinder 10 is supported by screws and bushings 11 from insulating members 12. Insulating members 12 are supported on cross-insulating members 13 which are in turn supported from the framework of the transmitter.

90 95 100 The opening or cut away portions 7 provided in cylindrical plate members 4 and 5

may be caused to coincide with each other or to depart from this agreement. The former position is that wherein the capacity between members 4, 5 and 10, 1 is of minimum value.

In the latter position, where the effective area is increased by closing the openings 7, the capacity is of maximum value. Member 5, as heretofore stated, is supported by arm 3. Member 4 is adapted to rotate by means of gear 22. Gear 22 engages with gear teeth provided on the exterior wall of plate 4. Gear 22 is carried on shaft 28, the latter adapted to turn in bearing part 21. Gear 23 is also carried on shaft 28, which gear is engaged with worm gear 24 mounted on the control shaft which turns through bearing 26. A shield 27 is provided around the gears to prevent sparking over to cylindrical plate member 10 and to socket 1. An eccentric bearing may be provided for shaft 28 to permit adjustment effecting the proper engagement of gear 22 with the gear teeth cut into the wall of cylinder 5. An annular shaped metallic member 14 is attached to socket 1 by angle 8. Annular shaped members 16 and 16a of suitable metallic material support and are electrically connected to cylindrical plate members 17, 17a and 17b. Cylindrical plate members 18 and 18a are supported by and electrically connected to annular shaped member 14. Cylindrical plate members 18 and 18a are spatially positioned with respect to plate members 17, 17a and 17b. Controlling means serving to hold plate member 17b in the proper position and for adjusting the capacitive relation between plate members 17-18 are illustrated in the figures to follow. Plate members 17, 17a, 17b, 18, 18a, 10 and the wall of socket 1 constitute a condenser, the capacity of which depends upon the effective capacity area of these members.

Fig. 2 is a diagrammatic plan view of the condenser system of our invention showing the mechanical arrangement for adjusting the position of plate members 4 and 4a. Thermionic tubes 2 and 2d having their anodes cooled by a circulating fluid are positioned in sockets 1 and 1d, respectively. Cylinders 4, 5 and 4a, 5a are concentric with the water jackets of tube sockets 1 and 1d respectively. Cylinders 10 and 10d are likewise concentric with respect to sockets 1 and 1d. Cylinders 10 and 10d are electrically connected to sockets 1 and 1d, respectively, and constitute one side of the balance condenser. Cylinders 4 and 4a are rotated simultaneously by means of crank 31 through insulated shaft members 29 and 29a. The shaft immediately associated with crank 31 cooperates with indicating mechanism consisting of bevel gears 32 and 33 and counter 34. Counter 34 is mounted so as to be visible through a window provided in panel 35. A knurled nut controls the engagement of worm gear 24a and part 31a. The latter provides means for readily

effecting the relative positioning of members 4 and 4a in the necessary relation to counteract dissimilar characteristics of thermionic tubes 1 and 1d.

Fig. 3 of the accompanying drawings shows a side view of the clutch mechanism for adjusting the relative positions of plate members 4 and 4a, shown in Figs. 1 and 2, previously referred to. The section of cylindrical plate member 10d which, similar to plate 10, is cut away, is shown in greater detail. This cut away portion is to prevent voltage flash-over between cylindrical plate members 3 and 3a illustrated in the other figures of the accompanying drawings.

In Fig. 2, guide rods are shown which run parallel with respect to the axes of cylinders 10, 10d, the upper ends of such rods extending through holes 50, 51 of plate member 49. The upper end of an adjusting rod 47 rests in bearing 49a which is of insulating material. This adjusting rod is mechanically associated with control rod 55, which in turn extends through panel 35 and is operably controlled by crank 31a.

The control mechanism for adjusting the position of plate members 17, 17a and 17b, shown in Fig. 1 is illustrated in Fig. 4 of the accompanying drawings. A duplicate arrangement of cylindrical plate members similar to members 17, 17a and 17b are provided for thermionic tube socket 1d and controlled in like manner. The control mechanism consists of a threaded rod 47 engaging with a threaded bore 46 in plate 49. Plate 49 is connected to plates 17a and 17d which are adjustable in relation to cylinders 10 and 10d. Bevel gears 53 are actuated by rod 47 and shaft 55. Shaft 55 and rod 47 rest in bearing member 52. Bearing 52 is supported by a cross member of suitable insulating material which is carried by insulating member 13a. The lower adjacent sections of cylindrical plate members 10 and 10d are cut away. Plate 49b is attached to cylindrical plate members 17a and 17d and movable therewith. The hole through plate 49b permits unrestricted vertical movement of plate 49 with respect to threaded rod 47. A bearing is provided in cross-member 49a for the upper end of rod 47. The control mechanism for plates 4 and 4a and the control mechanism for cylindrical plate members 17, 17a and 17b and similar plate members for socket 1d, may be controlled by common mechanical means whereby reduction gears or other means permit the proper relative movement of the plate members as determined by the frequency characteristics of the tubes, the associated circuits and capacity of the condenser units.

The condenser system of our invention is adapted to a variety of applications. Two individual condensers are provided immediately connected with each of the thermionic tubes. In the drawings two thermionic tubes

are shown, however it is obvious that one tube, or more than two tubes, may be employed. Thermionic tubes 2 and 2d may be associated with sockets 1 and 1d respectively and the latter positioned exterior to the condenser system. However, the arrangement shown utilizes a minimum of space and increases the capacity in that the tube sockets increase the effective area of the stationary plates.

10 Fig. 5 of the accompanying drawings shows schematically the operation of the condenser system of our invention. Condensers 1-4 and 1d-4a represent the condensers having the cut away openings heretofore referred to. Condenser plates 10 and 10d are electrically connected to condenser plates 1 and 1d, respectively, the latter corresponding to the tube sockets shown in Fig. 4. Plates 4 and 4a represent adjustable plates 4-5 and 20 4a-5a respectively shown in Fig. 2. Condenser plates 17a and 17d correspond respectively to cylindrical plate members 17a and 17d of Fig. 4. Condenser plates 17a and 17d are electrically connected as shown, which 25 connection corresponds to that provided by plate members 49 and 49a shown in Fig. 4. The schematic circuit diagram illustrates one application of the condenser system of our invention wherein the frequency characteristics of a balanced thermionic tube arrangement are controlled and whereby the circuits are neutralized to prevent inter-oscillation of the tubes. The neutralizing or balancing condensers are represented by plates 1-4 and 30 1d-4a respectively. The condensers for controlling the frequency characteristics of the oscillatory or amplifying circuit are represented by plates 10-17a and 10d-17d. It is obvious that the condenser system of our 40 invention may be employed in many different circuit arrangements and it is therefore not intended to limit our invention by the schematic circuit diagram shown.

We realize that many modifications of the 45 condenser system of our invention are possible without departing from the spirit of our invention. Any number of cylindrical plate members similar to members 4, 5, having openings which are controlled, may be 50 employed. Instead of cylindrical plate members, semi-cylindrical members may be employed wherein one of the semi-cylindrical members may be adjusted to give in capacity effect that of a complete cylinder. As to 55 number of plates, inter-plate insulation and supporting means, many modifications are possible. It is to be clearly understood that the embodiments of our invention are not to be limited to the foregoing specification or 60 to the accompanying drawings but only as defined in the scope of the appended claims.

What we claim as new and desire to secure by Letters Patent of the United States is as follows:

65 1. A condenser system comprising in com-

bination a metallic cylindrical plate member adjustably positioned concentric with a metallic cylindrical shaped thermionic tube socket and insulated therefrom, a metallic cylindrical plate member the outer wall of 70 which is frictionally positioned against the inner wall of said adjustable member, and said cylindrical plate members having cut away portions adapted to be superimposed for adjustments of minimum capacity value. 75

2. A condenser system comprising in combination a metallic cylindrical shaped thermionic tube socket electrically connected to a cylindrical shaped metallic member spacially positioned concentric with said socket 80 and a plurality of cylindrical plate members spacially positioned concentrically between said other member and said tube socket, and said plurality of cylindrical plate members being slidably positioned in respect to 85 each other and having cut away portions the adjustable relative position of which determine the capacity of said condenser.

3. A condenser system comprising in combination a metallic cylindrical shaped thermionic tube socket, a group of cylindrical metallic members spacially positioned concentrically with respect to said socket, each of said members having certain sections of the walls thereof cut away and means for adjusting the relative positioning of said sections. 90

4. A condenser system comprising in combination a metallic cylindrical shaped thermionic tube socket electrically connected to a 100 metallic cylindrical shaped member spacially positioned concentric thereto and semi-cylindrical plate members spacially positioned concentrically between said socket and said first mentioned member, said semi-cylindrical plate members electrically insulated from said other members and means for adjusting the capacitive area of said semi-cylindrical members in respect to said other members. 105

5. A condenser system comprising in combination a metallic cylindrical shaped thermionic tube socket electrically connected to a metallic cylindrical shaped member spacially positioned concentric thereto and semi-cylindrical plate members frictionally positioned one over the other and spacially positioned concentrically between said socket and said first mentioned member, said semi-cylindrical plate members electrically insulated from 115 said socket, and means for adjusting the capacitive area of said semi-cylindrical members in respect to said other members. 120

6. A condenser system comprising in combination a metallic cylindrical shaped thermionic tube socket electrically connected to a metallic cylindrical shaped member spacially positioned concentric thereto and semi-cylindrical plate members frictionally positioned one over the other and spacially positioned 125 130

concentrically between said socket and said first mentioned member, said semi-cylindrical plate members electrically insulated from said socket and means for adjusting the 5 capacitive area of said semi-cylindrical members by moving one member with respect to the other thereby approaching the effective area of a complete cylinder.

7. A condenser system comprising in combination a metallic cylindrical shaped thermionic tube socket, semi-cylindrical plate members slidably positioned one over the other and spacially positioned concentrically with respect to said socket and insulated 10 therefrom and means for moving one of said semi-cylindrical members in respect to the other whereby said semi-cylindrical members 15 additively approach the capacitive area of a cylinder.

8. A condenser system comprising in combination a group of cylindrical shaped metallic members adjustably positioned with respect to each other spacially positioned concentric with respect to the cylindrical shaped 20 anode of a thermionic tube and insulated therefrom, said members having openings through the walls thereof and means for adjusting the relative positions of said openings whereby the effective capacity area of said 25 members is controlled by said adjusting means.

9. A condenser system comprising in combination a group of cylindrical shaped metallic members adjustably positioned with 30 respect to each other spacially positioned concentric with respect to the cylindrical shaped anode of a thermionic tube and insulated therefrom, said members having openings through the walls thereof and means for adjusting the relative positions of said openings.

10. A condenser system comprising in combination a group of cylindrical shaped metallic members adjustably positioned with 35 respect to each other spacially positioned concentric with respect to the cylindrical shaped anode of a thermionic tube and insulated therefrom, said members having openings through the walls thereof, means for adjusting 40 the relative positions of said openings, a plurality of cylindrical movable plates in capacitive relation to a plurality of cylindrical stationary plates electrically insulated from said first mentioned cylindrical shaped 45 members and said movable plates adapted to be coaxially adjusted with respect to said stationary plates.

LOUIS A. GEBHARD.
CORRIE F. RUDOLPH.
